UNITED STATES PATENT OFFICE.

WALTER RYLANDER, OF AMERICUS, GEORGIA.

DESIGN FOR A LAMP.

Application filed March 28, 1922. Serial No. 1,423. Term of patent 3½ years.

To all whom it may concern:

Be it known that I, WALTER RYLANDER, a citizen of the United States, and residing at Americus, in the county of Sumter and State of Georgia, have invented a new, original, and ornamental Design for a Lamp, of which the following is a specification, reference being had to the accompanying drawing, forming part thereof.

The figure is a perspective view of a lamp showing my new design.

I claim:

The ornamental design for a lamp, as shown.

WALTER RYLANDER.
